UNITED STATES PATENT OFFICE

121,638

DESIGN FOR A DRESS ENSEMBLE

Maxwell A. Rudolph, Philadelphia, Pa.

Application May 25, 1940, Serial No. 92,609

Term of patent 3½ years

To whom it may concern:

Be it known that I, Maxwell A. Rudolph, a citizen of the United States, residing at Philadelphia, in the county of Philadelphia and State of Pennsylvania, have invented a new, original, and ornamental Design for a Dress Ensemble, of which the following is a specification, reference being had to the accompanying drawing, forming part thereof, wherein—

Fig. 1 is a front view of a dress ensemble, showing my new design;

Fig. 2 is a rear view thereof;
Fig. 3 is a front view of the dress of the ensemble shown in Fig. 1; and
Fig. 4 is a rear view of Fig. 3.

I claim:

The ornamental design for a dress ensemble, substantially as shown.

MAXWELL A. RUDOLPH.
